[57] CLAIM

The ornamental design for a replacement fishing rod tip, as shown and described.

DESCRIPTION

FIG. 1 is a front elevation view of a replacement fishing rod tip showing my new design;

FIG. 2 is a left side elevation view thereof;

FIG. 3 is a right side elevation view thereof;

FIG. 4 is a rear elevation view thereof;

FIG. 5 is a top view thereof;

FIG. 6 is a bottom view thereof;

FIG. 7 is a front elevation view of an alternate embodiment of a replacement fishing rod tip showing my new design;

FIG. 8 is a left side elevation view thereof;

FIG. 9 is a right side elevation view thereof;

FIG. 10 is a rear elevation view thereof;

FIG. 11 is a top view thereof; and,

FIG. 12 is a bottom view thereof.
